EGG BEATER

Richard B. Lienhard, Newington, Conn., assignor
to The Taplin Manufacturing Company, New
Britain, Conn., a corporation of Connecticut

Application December 15, 1939, Serial No. 309,426

2 Claims. (Cl. 259—131)

This invention relates to the frame construction of those culinary utensils which are furnished for beating eggs, cream, meringues, batter and kindred food constituents, which are commonly known as center drive egg beaters.

The object of the invention is to design the frame which carries the handle, drive gear, pinions and dashers of such an article, of elements which are relatively inexpensive to manufacture and which can be easily and quickly manipulated so as to be locked together into a firm and durable assembly.

In the accompanying drawing Fig. 1 shows a side view of a beater which embodies the invention.

Fig. 2 on larger scale is a detail section illustrating the manner of engaging the handle sections of the frame with the dasher section of the frame.

Fig. 3 is a similar view showing the lower ends of the handle sections of the frame and the upper ends of the dasher section locked together.

Fig. 4 is a section on the dotted line 4—4 on Fig. 3.

Fig. 5 is a section on the dotted line 5—5 on Fig. 3.

The frame of the beater illustrated comprises two side bars 1, a U-shaped rod 2 and a locking cap 3. The handle 4 is fastened between the upper ends of the side bars, the drive gear 5 is rotatably mounted between the side bars, and the dasher 6 and pinions 7 to which the dashers are secured, are rotatably supported by the rod, in a customary manner.

The lower ends of the side bars have tongues 8 that are bent angularly outward, and a short distance up from these tongues are holes 9. The upper ends of the dasher rod are bent to form outwardly projecting fingers 10 which are of a size to fit the holes 9.

The locking cap which covers and protects the pinions has a central transverse groove 11 through which the lower edge of the drive gear turns, and two transverse slots 12 of a length equal to the width of the tongued ends of the side bars and of a width equal to the thickness of the tongues. The inner edges of the slots have recesses 13 and the outer edges of the slots have recesses 14.

In assembling the elements of this beater the dashers and pinions are placed upon the dasher rod and the upper ends of the rods bent out to form the fingers 10. The cap is then located on the dasher rod over the pinions, the recesses 13 and 14 allowing the passage of the fingers at

the ends of the dasher rod through the cap. The tongue 8 of one side bar is, with the bar in a horizontal plane, placed in a slot 12 in the cap, as illustrated in Fig. 2, and the bar turned to a vertical position until the tongue 8 extends under the cap and the finger 10 at the end of the dasher rod springs into the hole 9 in the side bar, as seen in Fig. 3. The other side bar is then manipulated in the same way.

With both of the side bars vertical and practically parallel they may be joined together and held from separation by securing them to an interposed tubular thimble 15. The handle may then be fastened between the upper ends of the side bars, the driving gear located between the side bars and the crank spindle 16 passed through it and the side bars.

With the construction described the engagement with the side bars above the cap of the fingers at the ends of the dasher rod and the engagement of the tongues at the ends of the side bars with the under side of the cap hold the element from longitudinal separation, and the cap through which the side bars and dasher rod pass prevent lateral separation also twisting of the elements with relation to each other.

The invention claimed is:

1. A frame for a beater of the character described which comprises a pair of side bars having a handle secured between their upper ends and having outwardly extending tongues at their lower ends and perforations above the tongues, a yoke-shaped rod having dashers and pinions rotatable on its lower sections and having outwardly extending fingers at its upper ends, and a pinion enclosing cap having near its outer ends transversely extending slots with longitudinally extending recesses in their edges, said slots being of a size to receive the side bar tongues and the recesses being of a size to receive the dasher rod fingers, whereby the fingered ends of the dasher rod may be passed upward through the recesses and the tongued ends of the side bars passed downward through the slots outside of the ends of the dasher rod and the side bars turned upward until its tongues project outward against the under face of the cap and the dasher rod fingers spring outward into the perforations in the side bars, and the cap, the dasher rod and the side bars be locked thereby against separation in all directions.

2. A frame for a beater of the character described which comprises a pair of spaced side bars having outwardly extending tongues at their lower ends and perforations above said

tongues, a U-shaped dasher rod having outwardly extending fingers at its upper ends, and a cap having near its ends transversely extending slots with longitudinally extending recesses, said 5 tongues extending downward through said slots and projecting outward against the under face of the cap, and said fingers extending upward through said recesses inside of the tongues and projecting outward into the perforations in the

bars, said elements being held assembled by the engagement of the bars and rod ends with each other and with the walls of the slots and recesses in the cap and by the engagement of said tongues with the under face of the cap and the projections of said fingers into the perforations in the bars. 5

RICHARD B. LIENHARD.
